UNITED STATES PATENT OFFICE.

JOSEPH F. BATCHELOR, OF BALTIMORE, MARYLAND.

COMBINED CAR AND AIR-BRAKE COUPLING.

SPECIFICATION forming part of Letters Patent No. 307,902, dated November 11, 1884.

Application filed July 1, 1884. (No model.)

To all whom it may concern:

Be it known that I, JOSEPH F. BATCHELOR, a citizen of the United States, residing at Baltimore, in the State of Maryland, have invented 5 certain new and useful Improvements in Combined Car and Air-Brake Couplings, of which the following is a specification.

My invention relates to a combined car-coupling and fluid-pressure brake-coupling.

10 An object of the invention is to make provision whereby, when making up a train, to avoid the trouble of coupling the brake-pipes between each two cars of a train; and a further object is to so construct and combine the usual 15 car-coupling and a brake-coupling that the former will serve to keep the parts of the latter in connection.

The construction whereby the desired result is accomplished will be described in connection 20 with the accompanying drawings, which illustrate what is deemed the best means of carrying the invention into effect.

Figure 1 is a side view, partly in section, of the ends of two cars with the improved couplers connected. Fig. 2 is a top view of two 25 couplers separated. Fig. 3 is a front end view of brake-coupler. Fig. 4 is a longitudinal vertical section of the brake-coupler. Fig. 5 is a plan view of the valve.

30 The letter A designates the end of a car, and B the ordinary buffers between the cars. The draw-head C has the usual endwise movement by the operation of a slot, a, and a fixed bolt, b, passed through the slot. A spring, c, serves 35 to keep the draw-head pressed endwise toward the end of the car.

The car-coupling E, in this instance, consists of the well-known hooks, which are pivoted to the draw-head, and thereby have a lateral 40 movement. Any other known suitable form of car-coupler may be used instead of the hooks. Springs to bear on the side of the hooks may be employed, as usual, to keep the coupler-hooks engaged, and chains d and the usual levers (not shown) may be employed to uncouple the hooks. These parts are all well known. The car-coupler draw-head has a hollow front end, C', and a brake-coupling head, F, consisting of any suitable elastic material, like rubber, 45 is fixed to a shank, e, which is adapted to slide endwise into the hollow front of the draw-

head. A spring, f, within the hollow head keeps the brake-coupling head projected. The elastic head F has a circular face, g, and a central hole, g', for the passage of the fluid, air, 55 or steam, which operates the brake. When the brake-coupling heads of two cars come in contact, the springs f will press them together tightly, but will yield to allow the elastic head F on each to set against the outer front end, 60 h, of the draw-head, as shown in Fig. 1. As the heads are elastic, they will thus, together, and compressed between the draw-heads, produce an air-tight connection. The hollow draw-head has a passage, i, and a port, l, and 65 between them a valve, k. The valve consists of two circular plates, n, or one plate and a seat for it. The plates have two openings or ports, n', and one plate is fixed to a spindle, n'', which is adapted to make a quarter-turn. When the 70 valve is open, the ports n' in each plate coincide, and when closed the cut-offs n'' of one plate cover the ports of the other. The spindle n'' projects through the top of the draw-head, and has an arm, n', attached. A spring, 75 n'', bears against the arm and keeps the valve normally open. A lever, n'', is pivoted to the car-platform, and projects above it, and a chain, n', connects the lower end of the said lever and spindle-arm. By these or equivalent devices 80 the valve may be closed at any time by a person on the platform. The usual brake-pipe G extends along below the bottom of the car to the brake-cylinder. (Not shown.) As the brake-pipe is immovable, a flexible hose, F', 85 is used to connect the brake-coupling port l on the draw-head with the said brake-pipe, thereby providing for the endwise movement of the draw-head. From this description it will be seen that when the draw-couplers E on two cars 90 are connected, the brake-couplers F will also be in connection, as shown in Fig. 1, and said draw-couplers will keep the brake-couplers together.

To insure that the brake-coupler heads, when 95 approaching each other in the operation of coupling up, will come together properly, so that their faces g will exactly coincide, I employ a curved or slanting guide-arm, I, which projects from one side at the front end of the 100 draw-head. The operation of this projecting guide-arm to prevent lateral displacement will

be understood by reference to Fig. 2. As each of two approaching draw-heads has a projecting guide-arm, I, on an opposite side, neither draw-head can deflect laterally. I also employ 5 a groove, j, on the side of the draw-head opposite that whereon the guide-arm is attached. A portion of the groove has parallel sides p; but near the front end of the draw-head the sides of the groove curve or spread apart, as 10 at p', to form a flaring entrance. The guide-arm of one draw-head occupies the groove of the other. The upper and lower curved sides at the entrance of the groove serve to direct the arm I into the groove and prevent the 15 draw-heads from deflecting vertically. Thus by the guide-arms and grooves having curved sides or flaring entrance the brake-coupler heads are brought together properly.

In order to provide for connecting one of 20 these brake-couplers with any style of brake-coupler now in use, a special port, q, is made. A yoke, r, and screw s at the port serve either to stop the port or to connect therewith an ordinary hose-coupling. By this device a car 25 with my couplers may be made up in a train with cars with a different coupler.

The couplers are designed for use with air, steam, or vacuum brakes, and may therefore be used with the Westinghouse automatic 30 brake, for which it is adapted.

Having described my invention, I claim and desire to secure by Letters Patent of the United States—

1. The combination, substantially as set 35 forth, of a draw-head, an elastic coupling for fluid-pressure brakes on the front end of the draw-head, a connection for the passage of fluid between the said elastic coupling and the brake-pipe on the car, and a car-coupler to 40 connect the draw-head with another draw-head, whereby when the cars are coupled the

elastic coupling for the brakes will be compressed between the draw-heads.

2. The combination, substantially as set forth, of a hollow draw-head, a car-coupler attached to said draw-head, an elastic brake-coupling head on the front end of the draw-head, and a hole in the elastic head, which is in communication with the brake-pipe on the car. 45

3. The combination, substantially as set forth, of a hollow draw-head, a car-coupler attached to said draw-head, a brake-coupling head having a shank adapted to slide into the hollow draw-head, and a spring to press the 50 brake-coupling head outward. 55

4. The combination, substantially as set forth, of a draw-head, a brake-coupling attached thereto, a valve to open and close the passage in the said brake-coupling, and a lever on the car-platform, connected with the valve, whereby a person on the platform may at any time open or close the brake-valve. 60

5. The combination, substantially as set forth, of the draw-heads, a guide-arm attached 65 at one side, and projecting in front of each draw-head, and a fluid-pressure brake-coupling, and also a car-coupler, both attached to a draw-head.

6. The combination, substantially as set 70 forth, of a coupling for fluid-pressure brakes, and a head to which the coupling is attached, having at one side a guide-arm projecting in front and at the other side a groove for the reception of a guide-arm. 75

In testimony whereof I affix my signature in presence of two witnesses.

JOSEPH F. BATCHELOR.
